UNITED STATES PATENT OFFICE.

EUGÈNE SCHNEIDER, OF PARIS, FRANCE, ASSIGNOR TO SCHNEIDER & CIE., OF PARIS, FRANCE, A LIMITED JOINT-STOCK COMPANY OF FRANCE.

SAFETY APPARATUS FOR PREVENTING THE OPENING OF THE BREECH OF A GUN BEFORE THE RECOIL OF THE GUN-BARREL.

1,388,607.

Specification of Letters Patent. Patented Aug. 23, 1921.

Application filed December 28, 1920. Serial No. 433,658.

To all whom it may concern:

Be it known that I, EUGÈNE SCHNEIDER, a citizen of the Republic of France, resident of Paris, France, have invented new and useful Improvements in Safety Apparatus for Preventing the Opening of the Breech of a Gun Before the Recoil of the Gun-Barrel, which invention is fully set forth in the following specification.

10 This invention has for its object to provide an apparatus affording complete safety against hang fire, consisting of a device for engaging the handle of the breech-operating lever of guns, this engagement preventing all actuation of the said handle immediately the breech has been closed; the disengagement of the said handle takes place automatically on the recoil of the gun barrel.

15 The improved apparatus is applicable to gun breeches, the operation of which necessitates a movement of the handle of the breech-operating lever along its axis, followed by a pull upon said handle.

20 The invention is illustrated in the accompanying drawings, in its application to a gun breech mechanism of the known type of interrupted screw-threads.

25 Figure 1 is a fragmentary plan of a gun showing my invention applied thereto, the open and closed positions of the breech mechanism operating handle being shown in dotted and full lines respectively.

30 Fig. 2 is a sectional view on the line 2—2 of Fig. 1.

35 Figs. 3, 4, 5 and 6 are schematic side elevations partly in section showing the relative positions of the breech mechanism locking means, the safety apparatus, and the breech mechanism operating handle, at different points in the path of travel of said handle.

40 Fig. 7 is a schematic view partly in section showing the stop member moved out of the path of travel of the breech mechanism operating handle with the stop actuating bolt of the safety apparatus moved to its extreme outward position by the recoil of the gun barrel.

45 Fig. 8 is a schematic side elevation, partly in section, showing the relative positions of the safety apparatus and the operating handle when the latter is released and movable to open the breech of the gun.

Fig. 9 is a view similar to Fig. 2 showing the stop member of the safety apparatus moved out of the path of travel of the operating handle by engagement with the handle after the recoil of the gun barrel.

Fig. 10 is a schematic side elevation, partly in section, showing the stop member moved to a remote position with respect to the operating handle by manually operable means attached to the gun barrel.

50 As shown in horizontal section in Fig. 1 of the accompanying drawings, such gun breech mechanisms comprise a breech block A provided with screwthreaded sectors α alternating with plain sectors α' , corresponding respectively to screwthreaded and plain sectors β , β' of the breech screw B.

55 The breech block A is constantly held in a breech block carrier C, pivoted to the breech screw B by means of a hinge-pin C¹. It can rotate in the said carrier for the purposes of being screwed and unscrewed.

60 The operation of the breech mechanism is effected by means of a lever E pivoted on the hinge-pin C¹. By its rotational motion the lever E moves with it by means of a stud e, a slide block F guided in the carrier C, and to which it imparts longitudinal motion. This slide block meshes by means of teeth f with a toothed sector α^2 formed on the breech block A; it thus assures in the movements imparted to it by the lever E, the screwing and unscrewing of the breech block into and out of the breech screw.

65 When the screwing has been effected, the lever E, the carrier C, the slide block F and the breech screw A, turn together as a whole on the hinge-pin C¹ for the purpose of withdrawing the breech block from its lodgment in the gun barrel.

70 In order to avoid any unscrewing of the block A while the breech is closed, a catch is caused to couple together in a known manner the spring handle G of the lever E and a rib H formed on the carrier C.

75 As shown in detail in Fig. 2 which is an elevation partly in section on the line 2—2 of Fig. 1 the handle G is slipped on to a projection E¹ of the lever E and is held on this projection by a pin g movable in a buttonhole slot e¹. The spring G¹ has a constant tendency to keep the handle raised. 105 The handle is formed with an extension G²,

and with a nib g^2 projecting from the inner wall of the said extension. The engagement of the handle G, for the purpose of preventing any untimely unscrewing of the breech block A, is effected between the nib g^2 and the rib H of the carrier C.

In order that this engagement shall be effected automatically in the closing movement of the breech, the rib H situated on a level with the nib g^2 , when the latter is raised by the spring G¹, has a chamfered end h at its inner end. In the closing movement, the nib g^2 meets this chamfer, and is thereby depressed, and thus produces a compression of the spring G¹ of the handle. Successively the nib g^2 slides along the chamfer h of the rib, along the horizontal portion h^1 , and having arrived at the end of the rib, it leaves the latter and is caused to engage behind it by the action of the expansion of the spring G¹. This arrangement is known.

According to this invention, the said apparatus is combined with a complementary device which, when the breech is closed, and the handle G of the operating lever being engaged behind the rib H, prevents any depression of the said handle, and consequently its actuation by hand, so long as the gun barrel has not initiated its recoil.

The improved apparatus consists essentially of a spring stop I situated in the path of the operating handle G, and so arranged as to move out of the way of said handle in the closing movement of the breech, but to engage automatically with the underside of the handle immediately the breech is closed; the disengagement of said stop carried by the gun barrel being only rendered possible by the action of the recoil of the gun barrel.

In the illustrated practical embodiment of this invention, the stop I is slipped by means of a hub I¹ upon a bolt J movable in a box K fixed on the breech end of the gun barrel. The bolt J is acted upon by a spring J¹ which has a constant tendency to push the nose of the bolt outward and to compress the less powerful spring I², which latter has an opposite action upon the stop I. This spring I² is fixed at one end to the hub of the stop, and at its other end to the outer end of the box K; it acts both as an expansion spring and a torsion spring.

Normally the spring I² has a tendency to push the stop from left to right, that is to say, toward the axis of the gun barrel, and to rotate said stop member rearwardly to the position shown in Fig. 3. An extension i abutting against the end of a slot k formed in the box K, serves to limit the rearward inclination of the stop.

When the breech is closed, the nose of the bolt J bears against a rib M formed on or fixed to the guard plate N carried by the cradle O. This bearing of the bolt against the rib M keeps the said bolt pushed inward,

the spring J¹ being compressed. The rib M terminates at its rear end in an outwardly sloping ramp n upon which the nose of the bolt J slides at the end of the recoil of the gun barrel.

The improved apparatus operates as follows:—

When by the actuation of the lever E by means of the handle G, the breech block A has been engaged in the breech screw B, the said lever E—G occupies the position indicated in dot and dash lines in Fig. 1. The nose of the bolt J is in contact with the rib M. The spring J¹ is compressed, while the spring I² is expanded, the stop I being inclined toward the rear, as shown in Fig. 3.

On continuing to actuate the lever E—G by pushing it toward the breech screw, the breech block A is screwed into the breech screw B in the known manner above referred to. Toward the end of this operation the nib g^2 of the handle G meets the chamfer h of the rib H of the breech block carrier C; it slides along the said chamfer, thereby causing the depression of the handle, and the compression of the spring G¹ up to the moment when the nib becomes engaged with the underside of the horizontal portion h^1 of the said rib (Fig. 4).

At this instant the extension G² meets the stop I, and the continuation of the actuation of the lever E causes a forward tipping over of the stop and at the same time a sliding movement of the nib g^2 along the horizontal face h^1 of the rib H.

Immediately that, in this movement, the nib g^2 passes beyond the end of the rib H, the nib g^2 becomes free (Fig. 5.); thus allowing the spring G¹ to expand and to effect the rise of the handle. In this rising movement the nib g^2 engages behind the rear face h^2 of the rib H, and the stop I is caused by the action of the torsion spring I², to resume its upright position, namely, that shown in Fig. 6, where it bears against the heel g^3 of the extension G², at the same time as it bears under the heel g^4 formed by the notch provided in the said extension. The parts have assumed this position at the instant when the breech is completely closed. From that moment onward it becomes impossible to open the breech. Any pull exerted upon the handle G is prevented by the engagement of the nib g^2 behind the rib H, and the disengagement between G² and H is prevented by the extension G² abutting against the stop I. So long as the gun barrel has not recoiled, the opening of the breech is thus rendered impossible without a previous action upon a hereinafter described device for moving the stop I out of the way. On the recoil, the bolt J meets the ramp n of the rib M. In sliding along this ramp, the bolt is pushed outward by the expansion spring J¹ which is stronger than

the spring I^2 , with the result of moving the stop I to one side and bringing it into the position shown in Fig. 7.

Thus the lever $E-G$ can be operated to 5 open the breech, only from the instant when the gun barrel in its recoil, shall have moved the bolt J to the end of the ramp n .

On returning into battery position, the stop I which has been returned to the rear 10 by the torsion of the spring I^2 , is met by the lower end of the extension G^2 , that is to say, by the portion of this extension that projects below the heel g^4 , thereby preventing the stop from being returned toward 15 the axis of the gun barrel by the spring I^2 (as shown in Figs. 8 and 9.)

The bolt J can on the contrary move freely out of the way on contact with the ramp n and be pushed inwardly as shown 20 in Fig. 9.

It will be seen that in this position (the breech closed after the return into battery position) the stop I is moved automatically out of the way, and the breech can be opened 25 by depressing the handle G , followed by a pull toward the rear. Immediately this opening has been effected, the stop I is returned inward by the spring I^2 and is ready 30 to operate as a safety device when the breech shall have been closed again.

A device for moving the stop I out of the way, in the case of requirement, during 35 firing or during practice maneuvers, is illustrated in the various figures. This device comprises a cam P pivoted on a pin p fixed to the breech end of the gun barrel. This cam can be actuated by means of a spring handle P^1 that can be locked in one or the other position by the engagement of the 40 nose p^1 into one or the other of the two sockets Q or Q^1 (Fig. 2). When the handle is locked in the socket Q , the cam P is situated outside the path of the extension i of the stop I . By actuating the handle P^1 in 45 a clockwise direction, the cam P is caused to act upon the extension i , and the stop is caused to tip, as shown in Fig. 10, by moving it out of the path of the extension G^2 of the operating handle. The engagement 50 of the nose p^1 in the socket Q^1 assures the retention of the stop in its moved-away position.

The improved apparatus as described has 55 a great advantage over the known safety devices, the disengagement of which is effected on the recoil by the action of the meeting between a lever and a ramp. In these known devices, the meeting between the free lever and the actuating ramp, takes 60 place at a very high speed at the commencement of the recoil and gives rise to shocks which are frequently the cause of breakages. In the improved apparatus the safety bolt is in contact with its operating ramp 65 when the breech is in its closed position, and

it slides in contact with the said ramp from the very beginning of the recoil, and leaves it almost immediately. The meeting between the bolt and the ramp takes place then only toward the end of the return of 70 the gun barrel into battery position and therefore at a very low speed. Any accident which might produce a shock is by this means rendered impossible.

Having now particularly described and 75 ascertained the nature of our said invention and in what manner the same is to be performed, we declare that what we claim is:

1. In a safety apparatus for preventing movement of the breech mechanism of a 80 gun before recoil of the gun barrel, the combination of a cradle, a gun barrel carried within the cradle and provided with a breech mechanism, means for locking the breech mechanism in closed position made 85 effective by a longitudinal movement of the breech mechanism operating handle, and means operable to engage and prevent movement of said handle after said locking means has been made effective. 90

2. In a safety apparatus for preventing movement of a breech of a gun before the recoil of the gun barrel, the combination of a cradle, a gun barrel carried within the cradle and provided with a breech mechanism, means for locking the breech mechanism in closed position made effective by a longitudinal movement of the breech mechanism operating handle, means operable to engage and prevent movement of said handle after said locking means has been made effective, and manually operable means for moving said handle engaging means to a position remote from the handle, permitting opening of the breech mechanism prior 100 to the recoil of the gun barrel. 95

3. In a safety apparatus for preventing movement of a breech of a gun before the recoil of the gun barrel, the combination of a cradle, a gun barrel carried within the 110 cradle and provided with a breech mechanism, means for locking the breech mechanism in closed position and made effective by a longitudinal movement of the breech mechanism operating handle, means operable to engage and prevent movement of said handle after said locking means has been made effective, and means operable by the recoil of the gun to move said handle engaging means out of the path of travel of 120 said handle, permitting movement of the breech mechanism to its open position. 115

4. In a safety apparatus for preventing movement of the breech of a gun before the recoil of the gun barrel, the combination of a cradle, a gun barrel carried within the cradle and provided with a breech mechanism, means for locking the breech mechanism in closed position and made effective by a longitudinal movement of the breech 125 mechanism operating handle, means operable to engage and prevent movement of said handle after said locking means has been made effective, and means operable by the recoil of the gun to move said handle engaging means out of the path of travel of 130 said handle, permitting movement of the breech mechanism to its open position. 130

mechanism operating handle, a stop member rotatably and slidably mounted on the gun barrel and automatically operable to engage and prevent movement of the handle 5 after said locking means has been made effective, and means operable by the recoil of the gun to move said handle engaging means out of the path of travel of said handle, permitting movement of the breech mechanism 10 to its open position.

5. In a safety apparatus for preventing movement of a breech of a gun before the recoil of a gun barrel, the combination of a cradle provided interiorly with an extension, 15 a gun barrel carried within the cradle and provided with a breech mechanism, means for locking the breech mechanism in closed position and made effective by a longitudinal movement of the breech mechanism operating handle, means automatically operable to engage the handle and prevent movement thereof after said locking means has been made effective, and spring controlled means coacting with said cradle extension and operable by the recoil of the gun barrel to move 20 said handle engaging means out of the path of travel of the handle, permitting movement of the breech mechanism to its open position.

6. In a safety apparatus for preventing 30 movement of a breech of a gun before the recoil of the gun barrel, the combination of a cradle provided interiorly with an extension, 35 a gun barrel carried within the cradle and provided with a breech mechanism, means for locking the breech mechanism in closed position and made effective by a longitudinal movement of the breech mechanism operating handle, spring controlled means automatically operable to engage and prevent movement of the handle after said locking means has been made effective, and spring controlled means associated with said handle engaging means and the cradle extension and operable by recoil of the gun 40 barrel to automatically move the handle engaging means out of the path of travel of said handle, permitting movement of the breech mechanism to its open position after the gun barrel has returned to the battery 45 position.

Dated this 10th day of November, 1920.

In testimony whereof I have signed this specification.

EUGÈNE SCHNEIDER.
